UNITED STATES PATENT OFFICE.

HENRY W. VAN LEIR, OF PHILADELPHIA, PENNSYLVANIA, ASSIGNOR TO THE S. S. WENZELL MACHINE COMPANY, OF CHARLESTON, WEST VIRGINIA, A CORPORATION OF WEST VIRGINIA.

BOTTLE-WASHING MACHINE.

No. 895,918.

Specification of Letters Patent.

Patented Aug. 11, 1908.

Application filed October 10, 1907. Serial No. 396,823.

To all whom it may concern:

Be it known that I, HENRY W. VAN LEIR, a citizen of the United States, residing in Philadelphia, Pennsylvania, have invented 5 certain Improvements in Bottle-Washing Machines, of which the following is a specification.

My invention relates to that class of bottle washing machines in which the bottles are 10 confined in an inverted position in a clamping frame, and are moved up and down over the rotating brushes, the object of my invention being to provide simpler and more efficient means than those heretofore employed 15 in machines of this class for automatically imparting such up-and-down motion to the bottle-carrying devices. This object I attain in the manner hereinafter set forth, reference being had to the accompanying drawings, in which 20

Figure 1 is a perspective view of sufficient of a bottle washing machine of the type to which my invention relates to illustrate said invention; Fig. 2 is a plan view, on an enlarged scale, of those parts of the machine to 25 which the invention relates; Fig. 3 is a side elevation of the same, and Fig. 4 is a section on the line *a—a*, Fig. 3.

The machine has a base frame or bed 1 and 30 a top frame 2 connected together by vertical rods 3, 4 and 5, and said base frame or bed is also provided with a vertical frame 6, in which are formed bearings for a horizontal shaft 7 having fast and loose pulleys 9 and 10 35 for the reception of the driving belt.

A vertical shaft 11 is geared to said horizontal shaft 7 by means of bevel wheels 12 and 13, said vertical shaft also having a spur wheel 14 for driving the vertical brush-carrying spindles (not shown) which are suitably 40 mounted in a box or tank 15 and are contained within a telescopic casing 16 whose top plate 17 constitutes the lower member of the device for clamping the inverted bottles, 45 said plate having, at each side, bosses 19 which are vertically guided upon the vertical rods 3 and 4 of the frame and carry other vertical rods 20 which are connected to upper bosses 21, likewise guided on the rods 3 and 4 50 and provided with bearings for a shaft 22 having cams 23 which act upon the top plate 24 of the bottle clamping device, the latter

having bosses 25 guided upon the rods 3 and 4 and suspended from the upper bosses 21 by means of coiled springs 26. The lower 55 bosses 19 are connected by means of links 27 to counterbalanced levers 29, which are secured to a rock shaft 30, mounted in suitable bearings at the back of the box or tank 15 of the machine. All of these parts are common 60 to machines as heretofore constructed, and such machines have also been provided with means, driven from the vertical shaft 11, for imparting rocking movement to the shaft 30 and thereby effecting the desired vertical 65 movement of the inverted bottles during the operation of washing the same, and my present invention consists of a certain novel combination of parts for effecting this latter result. 70

Secured to the shaft 11 is a worm 31 which meshes with a worm wheel 32 upon a horizontal shaft 33, the latter being free to turn in suitable bearings 34 at the upper end of the vertical frame 6, and being provided at 75 one end with a disk 35 which is securely confined to the shaft so as to be caused to rotate therewith.

Secured to and projecting from the disk 35, at a fixed distance from the axis of the 80 same, is a crank pin 36 which passes through an opening in the enlarged lower end 37 of a rod 39, the latter being maintained in engagement with the crank pin by means of a nut 40 and washer 41, as shown in Figs. 2 and 85 3. The upper portion of the rod 39 has an enlargement 42 for the reception of a tubular sleeve 43, (see Fig. 4) said sleeve having, at one end, a flange 44 and being threaded at the other end for the reception of a nut 45, 90 whereby the sleeve can be rigidly clamped to the arm 39 when desired, the enlarged portion 42 of the arm, however, being slotted, as shown in Fig. 3, so that when the nut 45 is loosened the arm can be readily swung out of 95 engagement with the sleeve 43. The said sleeve 43 constitutes a bearing for a pin 46, which is shouldered and threaded at one end for the reception of a nut 47, as shown in Fig. 4, the other end of said pin 46 being adapted 100 to a segmental slot 49 in an arm 50 which is adjustably secured to the rock shaft 30 in a manner hereinafter described.

The pin 46 has a collar 51 bearing upon

one face of the arm 50 and said pin is threaded for the reception of a nut 52, between which and the other face of the said arm 50 is interposed a washer 53 (see Fig. 4) consequently the pin 46 can be adjusted to any desired position in the slot 49 of the arm 50, and can be rigidly secured to said arm in any of its several positions of adjustment thereon, a pointer 54, operating in conjunction with certain graduations on the outer face of the arm, as shown in Fig. 2, insuring accuracy of adjustment.

The arm 50 has a hub 55 which is mounted so as to be capable of turning on the rock shaft 30, but secured to said rock shaft, alongside of the arm 50, is another hub 56, which has a depending arm 57 (see dotted lines, Fig. 3) and the lower end of said arm 57 has a projecting bolt 59 which passes through a segmental slot 60 in the arm 50 and is threaded for the reception of a nut 61 bearing upon said arm and serving to clamp the same to the arm 57. While said arm 50, therefore, bears a certain relation to the arm 57 on the shaft 30, when the machine is in operation, this relation can be changed within certain limits by slackening the nut 61 and swinging the arm 50 on said rock shaft 30 in one direction or the other in respect to the arm 57.

The hub 56 of the arm 57 is secured to the rock shaft 30 in any suitable way, but by preference said hub is split, as shown in Fig. 3, and provided with projecting lugs 62 for engagement with a clamping bolt 63, in order to permit of ready and accurate adjustment of the hub 56 upon the rock shaft.

As the shaft 33 is rotated, rocking movements are imparted to the shaft 30 through the medium of the arms 57 and 50, the connecting rod 39, and the crank pin of the disk 35, and this rocking movement of the shaft 30 is caused to impart vertical reciprocating movement to the clamping frame carrying the inverted bottles, the extent of this movement being readily and accurately regulated to accord with the particular length of the bottles which are being washed, by proper adjustment of the tubular sleeve or bushing 43 in the segmental slot 49 of the arm 50.

The vertical terminations of the reciprocating movements of the bottle-carrying frame can be varied by adjustment of the arm 50 in respect to the arm 57, so as to insure proper contact of the brushes with the bottoms of the bottles when the bottle-carrying frame is at the lower limit of its movement, this adjustment being accomplished without in any way affecting the extent of vertical movement or length of stroke of said bottle-carrying frame.

By engaging a worm 31 on the vertical shaft 11 directly with a worm wheel 32 on the

shaft which carries the crank disk, a direct, positive and powerful driving movement of said crank disk is effected and the number of gears previously employed in devices of this class is materially reduced, with consequent reduction in liability to injury or disorganization of this part of the machine by reason of lack of care or rough treatment at the hands of the unskilled and careless attendants to whom bottle-washing machines are usually intrusted.

The adjustment of the upper end of the connecting rod 39 in respect to the arm 50, taken in connection with the graduated index and pointer, also tends to prevent mistakes due to ignorance in effecting adjustment of the machine for acting upon bottles of different lengths, and constitutes a more accurate and effective means of accomplishing this result than radial adjustment of a crank pin on a slotted disk, as has heretofore been proposed.

To facilitate the adjustment of the rod 39 in respect to the arm 50, said rod is extended above the arm and shaped so as to form a convenient handle 64.

It will be evident that so far as the attainment of the desired object of my invention is concerned it is immaterial whether the bolt 59 is carried by the arm 57 and the slot 60 is formed in the arm 50 or whether the construction is the reverse of this.

I claim:—

1. The combination, in a bottle-washing machine, of a main frame, a vertically reciprocable bottle-carrying frame, a rock shaft having a projecting arm with a segmental slot therein, means for connecting said rock shaft to the bottle-carrying frame, a shaft having a disk with a crank pin thereon occupying a fixed relation to the axis of said shaft, a rod hung to said crank pin, a pin carried by said rod and passing through the slot in the rock shaft arm, and means for securing said pin in different positions of adjustment in said slot.

2. The combination, in a bottle washing machine, of a main frame, a vertically reciprocable bottle-carrying frame, a rock shaft having a projecting arm, means for connecting said rock shaft to the bottle-carrying frame a shaft having a disk with a projecting crank pin, a rod connected to said pin and having an open-ended slot, a tubular sleeve or bushing adapted to said slot and provided with means for securing it to or releasing it from the rod, a pin free to turn in said bushing, and means for securing said pin to the rock shaft arm.

3. The combination, in a bottle washing machine, of a main frame, a vertically reciprocable bottle-carrying frame, a rock shaft having two arms, one fixedly secured to said

shaft and the other mounted so as to turn thereon, means for imparting rocking movement to the latter arm, and means for locking the two arms together in different relative angular adjustments and means for connecting said rock shaft to the bottle-carrying frame.

In testimony whereof, I have signed my name to this specification, in the presence of two subscribing witnesses.

HENRY W. VAN LEIR.
